No. 894,230.

PATENTED JULY 28, 1908.

T. C. PROUTY.
WHEEL FOR DOOR HANGERS.
APPLICATION FILED FEB. 25, 1905.

UNITED STATES PATENT OFFICE.

THEODORE C. PROUTY, OF AURORA, ILLINOIS, ASSIGNOR TO WILCOX MANUFACTURING COMPANY, OF AURORA, ILLINOIS, A CORPORATION OF ILLINOIS.

WHEEL FOR DOOR-HANGERS.

No. 894,230.

Specification of Letters Patent.

Patented July 28, 1908.

Application filed February 25, 1905. Serial No. 247,312.

To all whom it may concern:

Be it known that I, THEODORE C. PROUTY, a citizen of the United States, residing at Aurora, in the county of Kane and State of Illinois, have invented certain new and useful Improvements in Wheels for Door-Hangers, of which the following is a specification, reference being had to the accompanying drawings.

10 My invention relates to wheels for door hangers, and it has for its object to provide a new and improved wheel particularly adapted for use in door-hangers, but which may be applied to a variety of other uses. I accomplish this object as illustrated in the drawings and hereinafter described.

What I regard as new is set forth in the claims.

In the accompanying drawings,—Figure 1 is a vertical section, illustrating my improved wheel as applied to one form of door-hanger; Fig. 2 is a sectional view on line 2—2 of Fig. 1, certain parts being broken away; Fig. 3 is a vertical section on line 3—3 of Fig. 4; Fig. 25 4 is a side elevation of the wheel shown in Fig. 3, part of a door-hanger frame being illustrated; and Fig. 5 is a sectional view, illustrating the manner of forming the wheel.

Referring to the construction shown in Figs. 1 and 2,—5—6 indicate side-plates, which form the sides of the wheel and are circular in form. As shown in Fig. 1, they are also concavo-convex and provided with outwardly-bent rim-portions 7—8, respectively. The side-plates 5—6 are secured to the opposite sides of a central disk 9 which forms the tread of the wheel,—the rims 7—8 projecting beyond the tread, as shown in Fig. 1. The side-plates 5—6 and tread 9 are all mounted upon a hub 10 in the form of a sleeve, and the side-plates are held firmly in place on the disk by circumferential flanges 11—12 formed near the opposite ends of the sleeve 10, said flanges being struck up by 45 means of a suitable die, as disclosed in Fig. 5.

It will be understood that the side-plates are made of sheet steel, or other suitable material, as is also the hub 10,—said hub being best formed from a piece of sheet metal 50 rolled into cylindrical form. The tread 9 may be made of any suitable material, such as vulcanized fiber.

In order to prevent turning of the side-plates upon the disk 9, as well as to keep the plane of the tread perpendicular to the axis 55 of the hub, projections 14 are formed in each side-plate, which slightly penetrate the disk 9 and lock the parts against such motion one upon the other. Preferably three of the projections 14 are provided on each side-plate, 60 but a greater or less number may be employed, as desired. Furthermore, as shown in Fig. 4, the side-plates are so fitted to the disk 9 that the projections of one side-plate are in staggered relation to those of the other. 65

In Figs. 1 and 2 I have shown my improved wheel arranged for use in connection with roller bearings 15, running on an axle 16 mounted in a hanger 17. With this construction the hub 10 is tubular in order to receive the rollers 15.

In Figs. 3 and 4 I have shown my improved wheel mounted on a solid axle 18 having its ends provided with taper-bearings 19—20 arranged to run in a slot 21 in the side members 22—23 of another form of hanger. 75

That which I claim as my invention and desire to secure by Letters Patent is,—

1. A wheel, comprising a hub, concavo-convex side-plates mounted on said hub and 80 coacting to form a wheel, the convex faces of said side-plates being outermost, and flanges formed upon the outer surfaces of the hub between said side-plates and the adjacent end portions of the hub for securing said side- 85 plates upon the hub, said flanges being at a distance from the ends of the hub.

2. A wheel, comprising an intermediate disk and side plates at opposite sides thereof, said side plates being of greater diameter 90 than the tread portion, forming rims at opposite sides thereof, and having projections which engage said disk to prevent movement of said parts upon one another, the projections of one of said side plates being staggered with relation to those of the other, and 95 means for binding said parts together.

THEODORE C. PROUTY.
